ELECTRIC LIGHT FIXTURE

Mark N. Russell, Syracuse, N. Y., assignor to Pass & Seymour, Inc., Syracuse, N. Y., a corporation of New York.

Application June 26, 1937, Serial No. 150,441

7 Claims. (Cl. 240—85)

My invention relates to electric light fixtures and more particularly to fixtures in which the lamp-receptacle or "socket" is detachably mounted upon an internal annular flange of such a supporting shell as the well-known combined ceiling-band and shade-holder of hour-glass shape, internally flanged at its waist.

The construction that has long been practically standard for the above-stated type of fixture is substantially that shown in Patent No. 1,537,863 to H. J. Morey, granted May 12, 1925; that is to say, one wherein the ceiling-band shell has an internal, horizontal, uninterrupted supporting-flange, and the lamp-receptacle structure to be supported thereon comprises three separable pieces; namely, a porcelain block or core carrying suitable pull-switch mechanism together with the threaded lamp-socket shell, and two supplemental porcelain sleeve-members that jointly surround the core and clamp the assembly to said supporting flange; the upper sleeve member supportively receiving at its upper end a top-enlargement of the core and at its lower end bearing on the supporting flange, while the lower sleeve member, screwed onto the external threads of the lamp-socket shell, clamps against the underside of said flange. Also standard practice provides, in such constructions, an up-struck lug on the upper face of the supporting flange and a supplemental recess in the lower edge of the upper porcelain sleeve, to position the pull socket's chain-guide in appropriate relation to the chain-outlet of the ceiling band; but in various respects such heretofore-standard devices have drawbacks affecting their manufacture, their installation, and their maintenance of proper conditions under continued use, that I have overcome by my invention.

The general objects of my invention are to improve over this practically-standard construction, and over all other prior constructions of this general type of electric light fixture of which I am aware, in providing more adequate and reliable clamping of the lamp-receptacle to its supporting flange; minimizing production cost of the lamp-receptacle unit; facilitating the wiring and mounting of the receptacle, for reduced labor-cost in installation; and attaining other advantages of which more will be said later.

To these ends my invention consists in the features of construction and combinations of parts hereinafter set forth and claimed, reference being had to the accompanying drawing wherein I have illustrated a single embodiment of my in-

vention for purposes of full disclosure, and wherein:

Figure 1 is a vertical section of the assembled supporting-shell and lamp-receptacle on a diametric plane indicated by line 1—1 of Fig. 4;

Fig. 2 is a perspective view of the receptacle unit with its parts in the positions shown in Fig. 1;

Fig. 3 is a similar perspective with clamping and shielding parts swung to open position, and with a dotted showing of an intermediate position in the course of opening;

Fig. 4 is a plan view, broken away to show some of the parts in fragmentary section on line 4—4^a of Fig. 1, with the receptacle parts in clamping position; and

Fig. 4^a is a similar and complementary view showing the receptacle parts in preliminary, entering position, from which position the receptacle will be turned about its axis, as indicated by an arrow, before being clamped to the supporting-flange.

In the drawing 10 indicates the supporting shell, shown as of a conventional "hour-glass" design, made of sheet metal, with its ceiling-band section 11 and its shade-holder section 12 seamed together at the waist in usual fashion, conveniently to form the internal, horizontal, receptacle-supporting flange 13. This flange has parallel, flat upper and lower surfaces and desirably, for purposes of the preferred embodiment of my invention illustrated herein, has two diametrically opposed openings 14, notched into its inner margin, to permit easy passage therethrough of clamping parts on the lamp-receptacle hereinafter described.

15 indicates in general my novel lamp-receptacle, the insulating body of which provides, in a single-piece porcelain construction, a head-enlargement 16 and a smaller-diameter neck 17; there being a flat shoulder 18 between them to bear upon the supporting-flange 13 when the neck is slipped through the flange orifice in mounting the receptacle.

The head 16 as herein shown is designed to receive a conventional pull-switch mechanism in its central chamber 21; accommodation for the pull-chain 22 and for the pair of wiring terminals 23, respectively, being afforded by a slot 24 and by a pair of recessed bays 25; and the neck 17 of the unit is cylindrically hollowed to accommodate the lamp-receiving outer contact 26 of any conventional type, not necessarily restricted to the threaded type herein shown.

To receive and cooperate with the body-carried

clamping unit 30, to be later described, the head of the insulating body is shaped to provide opposed flats 27 approximately tangential to the circumference of the neck 17; a stout stop-pillar 5 28 is formed between the chain-slot 24 and the adjacent flat 27; and longitudinal side grooves 29 extend along the lower portions of the respective flats and into deepened extensions of such groove in the upper part of the neck 17, with 10 the two levels of each block connected by an inclined ramp or radial clamp-camming surface 29'.

The particular clamping unit 30 herein shown (which is also equipped for desirable functioning 15 as an insulating cover for the switch-recess 21 and as a shield for the wiring terminals 23) comprises a pair of clamp-dogs 31 mounted on the circular end-enlargements or turning-disks 32 of the diametrically opposed, longitudinal, 20 springy clamp-arms 33; these arms being carried by a cross-head 34 that extends diametrically over the top of the insulating block or body and which may be raised or lowered from above such body by an adjusting screw 35; such 25 screw being threaded through the cross-head and at its lower end swivelly engaged with a plate 36 that, in turn, is arranged to find bearing on the top of the insulating body of the receptacle.

In further detail, the cross-head 34 and the 30 longitudinal arms 33 of the clamping unit are preferably made in a single U-shaped piece, with the cross-head suitably stiffened as by a rib 34'; each arm 33 of the clamp being in-bent for a short length 38 near its lower end, so that 35 it stands at an acute angle to its juncture with the corresponding end-disk 32 on which one of the clamping dogs 31 is mounted.

Thus, when the cross-head 34 of the clamp-device is lowered, the dog-carrying disks 32 of 40 arms 33 recede into the deep end of grooves 29, in the neck portion of the unit, and in this condition the unit has its neck inserted through the orifice in the supporting flange 13 of the shell when the parts are being assembled. To preserve 45 wall-strength of the head and neck, and a very substantial protrusion of the clamp dogs from their carrying-arms, I prefer that the dogs should protrude somewhat even under full retraction, and therefore notch the supporting flange of the 50 ceiling-band structure, as at 14, to permit the dogs to readily pass below the level of the flange; and when this partial assembly has been made the lamp-socket unit is rotated to Fig. 4 position from the position shown in Fig. 4^a, as indicated 55 by the arrow on the latter figure, so as to bring the pull-chain slot 24 into proper relation to the chain-outlet opening 22' of the ceiling-band and to position both clamping dogs below solid segments of the supporting flange 13.

Turning the clamping screw 35 to raise cross-head 34 will result in firmly and effectually clamping the flange between the dogs 31 and the shoulder 18 of the lamp-receptacle body; the fine screw thread and the direct vertical lift of 60 the clamp insuring that the dogs 31 may bite very strongly against said flange. Additionally, the stated vertical lifting of the clamp device will ride the lower ends of its arms 33 up the ramps 29' to the position shown in Fig. 1, and 65 the resultant cam-compelled radial movement of the disks 32 may enhance the efficiency of the clamping, by the pressing thereof against the edge of the flange.

For the additional advantage of using the 70 clamping unit as a cover for the open end of

the lamp-receptacle body, and also as an insulating shield for the wiring terminals, the plate 36 of the clamp-structure is made to cover completely the top opening of the receptacle-body, except that a small portion of the cover-plate 5 is cut away as at 39 to accommodate the leading in of the feed-wires 41. And additionally, the cover-plate has two down-turned extensions or guards 40, positioned to overlie the respective bays 25 of the wiring terminals when said cover 10 is "closed"; the cover-plate being made non-rotatable with respect to the U-shaped clamping member by engagement of the flat arms 33 of said member against straight edge-portions 41 15 of the plate. A suitably contoured and molded piece of thin insulating material, 44, is mounted securely on the underside of the cover-plate and substantially conforms to its perimeter, and suitable shield portions or tabs, 45, of said material, shaped for substantial conformity with the bays 20 25 for the wiring terminals, are down-bent at the margins of said head and are braced against outward displacement by the respective guards 40 of the plate.

The entire shielding and clamping device above 25 described may be moved, however, to give free access to the switch parts and to the wiring terminals in installing or repairing the unit; the upper ends of guide-grooves 29 for the clamp arms being so located that when the circular 30 disks 32 are fully raised (as shown in dotted lines in Fig. 3) the clamping unit assembly may be pivotally swung to the open position shown in full lines in said figure. Complete detachment of the cover-and clamp assembly may be made, 35 but is practically never necessary.

It will be understood that the supply wires 41 for the fixture are brought through the surface to which the fixture is to be applied, with enough slack to permit of their being very readily connected to the terminals of the lamp-receptacle when the cover and locking parts of the latter are in the open position last referred to.

Thus, to install the complete fixture, the lamp-receptacle unit, with its cover-and-clamping 45 structure thrown to open position shown in full lines in Fig. 3, first has its terminals 23 connected to the wires 41; next has its cover closed to Fig. 2 position; then is slipped into the ceiling-band shell, with its clamping parts in lowered 50 position; next is turned as indicated by the arrow on Fig. 4^a to align chain-slot 24 with the ceiling-band's chain-outlet 22'; after which the screw 35 is operated from above the receptacle to lift the clamp-structure to clamping position shown 55 in Fig. 1, whereupon the completed assembly is ready for mounting in any convenient way in its intended position on the ceiling or wall.

It will be noted that while, by springing the arms 33 of the clamping structure completely 60 out of the longitudinal guide grooves 29, the clamping device may be completely removed, it is, for all practical purposes of handling the receptacle, a permanently mounted part thereof and merely is slidable along and pivotable on the 65 receptacle body; which feature, together with others heretofore mentioned, contributes to the time-saving facility of mounting the unit receptacle structure in its ornamental supporting shell.

Further it will be noted that the unitary construction of the receptacle body, ordinarily molded of porcelain, makes for low production cost; as does also the ample accessibility of the interior chambers for assembly of the electrical 70 75

parts in the manufacture thereof; while the provision of the openable cover-plate and of the insulated coverage of the bays for the wiring terminals insures adequacy of the protective insulation. In this last-mentioned connection it will be seen that the insulating material underlying the metal cover-plate protrudes somewhat beyond the edges of the wire-receptive opening 39 in the latter, to further the insulating characteristics of the device; and also that the somewhat protruding pillar 28, forming one wall of the pull-chain slot, constitutes an additional insulating safeguard.

I claim:

1. An electric light fixture of ceiling-band type comprising a shell having an internal open-centered flange for positioning a lamp-receptacle, and a lamp-receptacle structure for making demountable clamping connection with said flange; said receptacle having an insulating body provided with a neck-portion adapted to be passed downwardly through the opening of said flange and an upper portion providing at its bottom a shoulder adapted to bear directly on the upper side of said flange; and clamping means carried by said body and movable axially thereof, said clamping means including a pair of clamp-dogs normally positioned below the flange level and adapted to engage the underside of said flange when moved upwardly, arms extending from said clamp-dogs upwardly along said body and above it, and a single manipulative means accessible from above the receptacle body operatively associated with both said arms to raise 35 and lower the clamp-dogs into and out of clamping engagement with the underside of said flange.

2. An electric light fixture of ceiling-band type comprising a shell having an internal flange apertured and oppositely notched for receiving and positioning a lamp-receptacle, and a lamp-receptacle structure for making demountable clamping connection with the flange; said receptacle having a body providing a lower portion adapted to pass through the orifice of said flange and an upper portion providing a shoulder to bear directly on said flange, clamping means carried by said body and comprising a pair of diametrically opposed arms extending axially along the body from above its top to below its shoulder and having their lower ends provided with clamp-dogs adapted to pass through said notches and normally lie below the shell-flange level, said lower ends being movable both radially and axially between unclamped position and a clamped position engaging said dogs with the underside of said flange and pressing said arms radially against the edge of said flange, and means including a single manipulative device accessible from above said body operatively connected with the upper part of both said arms for simultaneously moving them.

3. An electric light fixture comprising a shell having an apertured internal flange for positioning a lamp-receptacle, and a lamp-receptacle structure for making demountable clamping connection with said flange, said receptacle having a body providing a neck portion adapted to pass through the orifice of said flange and an upper portion adapted to bear on said flange and having longitudinal grooves in opposite sides of said body extending above and below the upper portion's plane of bearing on the flange, a U-shaped clamping member providing clamping dogs near the free ends of its longitudinal arms, said arms

slidably engaging said grooves and having their cross-connection located above said body, means associated with said U-shaped member for adjusting it longitudinally with respect to the body, and camming formations in said body-grooves 5 for forcing the dog-carrying ends of said arms radially outward as the dogs approach from below their position for clamping against the underside of said flange.

4. In a lamp-receptacle adapted to be clamped to an apertured supporting flange of a ceiling-band-fixture shell, an insulating, lamp-receptive body having a laterally projecting bearing surface above its lower end and opposed longitudinal grooves along its surface extending above and below said bearing surface, a longitudinally movable clamping device having a cross-head above said body, downwardly extending springy arms guided in said longitudinal grooves and clamp dogs projecting from said arms in position normally below the body's said bearing surface, manipulative means accessible above and bearing upon the top of said body for raising and lowering said cross-head; and camming formations in said body grooves for springing the arm-ends 20 25 outwardly as the clamp-dogs approach, from below, the plane of the body's bearing surface.

5. In a lamp-receptacle adapted to be clamped to an apertured supporting flange, an insulating, lamp-receptive body having a hollowed head carrying wiring terminals, a hollowed neck carrying lamp-socket contacts and a laterally projecting bearing shoulder between the head and neck, a combined clamping and shielding unit carried by said body and arranged for longitudinal sliding 30 35 movement thereon into and out of locking engagement with the underside of a receptacle supporting flange and for bodily swinging movement to displace its upper portion laterally from shielding position, said unit including a shielding 40 member to overlie and bear upon the top of said body, clamp-adjusting means connected with said shielding member for bodily lateral displacement therewith, and clamping means for engagement with the underside of a supporting flange 45 and arranged to slide longitudinally and to rock laterally relative to said body, said clamping means being operatively connected to said clamp-adjusting means for vertical clamping adjustment thereby and to bodily displace it laterally 50 when the upper end of said clamping means is rocked with respect to the body.

6. Structure as set forth in claim 5, wherein the head of said body has lateral openings for access to the wiring terminals, said shielding member has pendant portions to substantially cover said lateral openings and the connected assembly of clamping means, clamp-adjusting means and shielding means is longitudinally 55 movable on the body sufficiently to raise said guard-portions above the body before the assembly is laterally rocked.

7. In a lamp-receptacle adapted to be clamped in an apertured supporting flange, an insulating body having a neck of smaller diameter and a head of larger diameter connected by a bearing shoulder, connected pull-switch parts and terminals mounted in said head and lamp-socket contacts arranged in said neck; said body having 65 70 opposed longitudinal grooves in its outer surface extending above and below said shoulder, and a combined clamping and shielding unit carried by said body and arranged for longitudinal sliding movement in said grooves and for rocking 75

- movement when in raised position to bodily dis-
place the upper part of said unit from normal
position overlying said head, said unit compris-
ing a U-shaped member having a cross-head por-
tion normally crossing above the head of the
body, longitudinal arms engaging said body-
grooves and at their lower ends carrying respec-

tive clamping dogs; a plate to bear on the top
of the body's head and an adjusting screw ac-
cessible at the upper end of the structure adjust-
ably connecting said cross-head and said cover-
plate.

MARK N. RUSSELL.
